UNITED STATES PATENT OFFICE.

SAMUEL AUGUSTINE DE NORMANVILLE, OF EALING, AND LESLIE HARcourt KENT,
OF STANMORE, ENGLAND.

VISUAL WEATHER-SCREEN.

1,340,025.

Specification of Letters Patent. Patented May 11, 1920.

Application filed December 10, 1918. Serial No. 266,173.

To all whom it may concern:

Be it known that we, SAMUEL AUGUSTINE DE NORMANVILLE and LESLIE HARcourt KENT, both subjects of the King of Great Britain, residing at Ealing, Middlesex, England, and Stanmore, Middlesex, England, respectively, have invented certain new and useful Improvements in Visual Weather Screens, of which the following is a specification.

This invention relates to improvements in visual weather screens—forming part of our application filed May 8, 1917, Serial No. 167,381, allowed Sept. 12, 1918, in which a transparent disk is rotated so that rain and spray driving against it are thrown off under centrifugal action.

The object of the present invention is to facilitate the application of a screen of the above type to existing windows, screens or look-out apertures, or as a face guard in the open, and preferably in such a manner that the device can be removed readily from its support for storage when not required, and also preferably so that when replaced for use it is connected automatically with the source of power by which it is driven.

One embodiment of the invention, in which electric power is used to drive the device, is illustrated by the accompanying drawings in which Figure 1 is a sectional side elevation showing the device applied to a motor-car screen.

Fig. 2 is a plan partly in section of a bracket for supporting the device and provided with electric contacts, and

Fig. 3 is a front elevation on a reduced scale of the device detached.

In this form a transparent disk 10, with its spindle 14, spindle bearing 13, pedestal 2 and a motor 16 are all arranged as a self-contained unit detachable for stowage purposes. Means are also provided by which the act of placing the unit in position completes automatically an electrical connection for the motor. In this form the disk 10 clamped between the nuts 15, 15, rotates with the spindle 14 which is carried in bearings 13, on the head of the pedestal 2. The electric motor 16 in the base of the pedestal drives a shaft 17 fitted with a bevel wheel 37 which engages with a bevel wheel 36 on the spindle 14. The lower end of the motor shaft runs in a step bearing 48. The motor 16 with the pedestal 2, and disk 10, are sup-

ported by a bracket 44 mounted in any convenient manner in front of the lower rail 162 of the existing motor car or other screen 1. The bracket has a split ring 45 adapted to be tightened by a screw 46 so as to clamp 60 firmly a cylindrical extension 47 on the motor 16. Contact plugs 48, screwed into insulating bushes 55 in the motor casing to allow for adjustment, are adapted to enter holes 51 in contact plates 50 mounted on an 65 insulating block 52 screwed to the bracket 44. The leads from an electric cable 54 are connected by terminal screws 53 to the plates 50. The inner ends of the plugs 49 engage with the motor terminal screws 56 on an 70 insulating block 57 mounted inside the motor casing.

When the screw 46 is slackened the unit can be removed, as indicated in Fig. 3, and the electric contact will be broken, whereas 75 when the unit is replaced the plugs 49 enter the holes 51 in the plates 50 and contact is made automatically no skill being required on the part of the user.

A guard 58, preferably faced on its edge 80 with rubber 62 to bear against the car screen 1, is provided for the purpose of preventing moisture passing down the screen 1 between it and the disk 10. The guard 58 is conveniently carried by wires 59 supported by a 85 collar 60 clamped between a cap 61 and the head of the pedestal 2.

We claim:

1. A visual weather screen comprising a transparent disk having a spindle, a pedestal 90 for supporting said spindle, means for driving said spindle comprising an electric motor, said pedestal being carried by said motor, a flange on said motor, a bracket adapted to embrace said flange to support said motor, 95 said bracket having contacts in connection with a source of electric current and being adapted to make contact with the terminals of the motor when said motor is placed on said bracket, substantially as and for the 100 purpose hereinbefore set forth.

2. A visual weather screen comprising a transparent disk having a spindle, a pedestal for supporting said spindle, means for driving said spindle comprising an electric 105 motor, said pedestal being carried by said motor, a cylindrical flange on said motor, a bracket for embracing said flange to support said motor, said bracket being in the form of a split ring, means for clamping 110

2
said ring on to said flange, perforated contact plates carried by said bracket, and terminals on said motor in the form of plugs adapted to enter the perforations of said contact plates when the motor is placed on said bracket, substantially as and for the purpose hereinbefore set forth.

3. In combination a stationary transparent screen, a rotary transparent disk, having 10 a spindle, a pedestal for supporting said spindle with the disk in close relation to said screen, an electric motor connected to said pedestal for driving the aforesaid spindle, a bracket on the aforesaid screen for sup-

porting said motor and pedestal, and means for preventing ingress of moisture between said screen and transparent disk, substantially and for the purpose hereinbefore set forth.

In testimony whereof we have signed our names to this specification in the presence of two subscribing witnesses.

SAMUEL AUGUSTINE DE NORMANVILLE.
LESLIE HARCOURT KENT.
